DESIGN FOR A HAT

Marinette Blanc, New York, N. Y.

Application January 12, 1940, Serial No. 89,441

Term of patent 3½ years

To all whom it may concern:

Be it known that I, Marinette Blanc, a citizen of the United States of America, residing in New York city, in the Borough of Manhattan, county and State of New York, have invented a new, original, and ornamental Design for a Hat, of which the following is a specification, reference being had to the accompanying drawing, forming part thereof, wherein

I claim:

The ornamental design for a hat, substantially as shown.

MARINETTE BLANC.
